UNITED STATES PATENT OFFICE.

HENRY E. HONEYWELL, OF ST. LOUIS, MISSOURI.

AIR-SHIP.

SPECIFICATION forming part of Letters Patent No. 784,161, dated March 7, 1905.

Application filed July 6, 1903. Serial No. 164,424.

To all whom it may concern:

Be it known that I, HENRY E. HONEYWELL, a citizen of the United States, residing at St. Louis, in the State of Missouri, have invented 5 a new and useful Improvement in Air-Ships, of which the following is a specification.

My invention relates to an improvement in air-ships, and has for its object to produce a compact and thoroughly reliable dirigible air- 10 ship in which the propelling force is practically applied to the best advantage for obtaining speed, insuring steadiness, and controlling the movements of the vessel.

The invention consists in features of nov- 15 elty, as hereinafter described and claimed, reference being had to the accompanying drawings, forming part of this specification, wherein-

Figure 1 is a side elevation of my improved 20 air-ship; Figs. 2 and 3, front and rear end elevations, respectively, thereof; Fig. 4, a detail view, to enlarged scale, corresponding to that seen to the left in Fig. 2, of one side of the framework (broken away) of the aeroplane 25 with its operating-arms forming part of my invention and showing its hinged junction with the main frame of the air-ship; and Fig. 5, a side view thereof as seen to the left in Fig. 1; Fig. 6, an inverted plan of the air- 30 ship; Fig. 7, a top plan, to enlarged scale, of a portion of the main frame, showing preferable means for securing the fabric composing the balloon or gas-bag thereto; and Fig. 8, a cross-section thereof on line 88 in Fig. 7.

Like letters and numerals of reference denote like parts in all the figures.

a represents the balloon or gas-bag of my improved air-ship, which when inflated is preferably of an elongated semipear shape, as 40 shown, having its largest and uppermost convex portion or volume 1 at the stern and adjacent forward portion of the air-ship and its remaining elongated convex portion or volume 2 gradually diminishing from the part 1 45 to a straight horizontal transverse edge, or practically *nil*, at the forward end or bow 3.

The bottom 4 of the balloon *a* is practically flat, except as otherwise constrained by the pressure of the contained gas.

The envelop of the gas-bag *a* is composed 50 of suitable fabric 5, which is preferably doubled or folded on itself at its lower horizontal surrounding edge or base 4, where it is strengthened by a marginal wire 6, (see particularly Figs. 7 and 8,) inserted in the fold 55 between the layers of the fabric 5, and beyond the wire 6 the fabric 5 is strongly sewed together by preferably double rows of stitching 7. Through the double layers of the fabric 5, between the wire 6 and stitching 7, are 60 inserted at suitable distances apart preferably metal eyelet-rings 8.

Around the gas-bag *a*, opposite or adjacent to its base 4, is arranged a frame or bar *b*, composed, preferably, of light metal tubing of 65 varying thickness and practically integral throughout.

Through the eyelet-rings 8 of the gas-bag *a* and around the frame *b* consecutively over and under is passed a cord or wire 9, which 70 on being tightened firmly secures the gas-bag *a* to the frame *b*.

To the forward end 3 of the frame *b* or "bow" of the air-ship is hinged one end of an aeroplane *c*, having a framework 10, of 75 preferably light metal tubing, which is covered with suitable fabric 11, the sides of its framework 10 tapering or diminishing toward its forward or outer free end conformably to the sides of the main frame *b* and the upper 80 and lower surfaces of the aeroplane *c* forming practically a continuation of the corresponding surfaces, respectively, of the gas-bag *a*.

To each side of the framework 10 in proximity to its hinge 3 are fixed an upper arm 12 85 and a lower arm 12', from the outer free ends of which respectively pass cords 13 13' (indicated by broken lines) to within reach of the aeronaut, so that by pulling on the cords 13 or 13' the aeroplane *c* can be raised or lowered 90 on its hinge 3 to any desired angle with the frame *b* for raising or lowering the air-ship at its forward end or bow accordingly.

From the frame *b* at a suitable distance therefrom and preferably in or about a vertical line passing through the center of gravity of the inflated gas-bag *a* is suspended by braces 14 a platform or car *d*, which supports 95

the aeronaut and other necessary equipment of the air-ship and on which are fixed the propeller-motors *e*.

The propellers *f*, preferably twin screws, 5 are fixed at the stern end of the gas-bag *a* on the outer ends of shafts *g*, which are mounted in bearings *h*, parallel or thereabout and longitudinally with the base 4 of the gas-bag *a* in close proximity thereto, so that the thrust 10 of the propellers *f* on the atmosphere is approximately transmitted along the longitudinal axis of the gas-bag *a* instead of at a considerable distance therefrom, whereby the air-ship is propelled more directly and to the best 15 advantage for insuring steadiness thereto, or, in other words, the balloon or gas-bag *a* is under control and less liable to become unmanageable when subjected to the varying conditions of atmospheric currents and storms.

20 The bearings *h* are formed in or fixed to a horizontal cross-bar 14', which connects the braces 14 thereof to each other, and thereby acts as a transverse brace to the frame *b*.

Rotation may be imparted to the shafts and 25 propellers *f* *g* from the motors *e* by the bevel-gearred wheels 15 15' and counter-shaft 16 (shown in Figs. 1 and 3) or by any other suitable well-known mechanism.

It is to be here noted that the combined 30 weight of the car *d*, with its appurtenances, is so arranged that on the ascent of the inflated gas-bag *a* therewith the bottom 4 of the gas-bag *a* normally assumes and is held at an inclination upward from the horizon at the 35 stern to the front end or prow of the gas-bag *a*, as clearly shown in Fig. 1, whereby on the forward movement of the air-ship by its propellers *f* the prow of the gas-bag *a* operates as a wedge in cleaving the air, or, in other 40 words, by this means the air impinges upon both the upper and lower surfaces of the gas-bag *a*, thereby insuring and maintaining its stability and rectilinear progression in the desired direction, besides rendering the action 45 of the aeroplane *c* more sensitive and effective in directing the prow of the gas-bag *a* upward or downward, whereas when the bottom of the gas-bag lies in a horizontal plane, as usually the case, the air acts normally only 50 upon its upper surface, which consequently tends to depress the forward end of the gas-bag without any counteracting resistance on its under side, so that in the event of a collapse of the balloon the bottom of the gas-bag 55 is caused by the upper air-pressure to descend suddenly, whereas with the inclined bottom *b* of the gas-bag *a*, which in case of the escape of the gas remains intact, the bottom *b* is prevented by the lower air-pressure from a sudden descent at its front end and with the aid 60 of the propellers *f* and aeroplane *c* acts as a parachute for insuring its gradual descent, with the car *b* and its appurtenances, to the ground in safety.

65 For insuring the rigidity of the frame or

bar *b* arms 17 project therefrom and are connected to each other and to the frame *b* at a suitable distance along the latter toward its forward and rear end, by wire bracing 18. Wire braces 19 also extend from the frame *b* 70 to the platform *d*, or any other suitable system of bracing may be used.

i is a rudder which is located centrally and at right angles to the base 4 of the gas-bag *a* in proximity to its rear end or "stern" of the 75 air-ship.

The rudder *i* is hinged, or, in other words, held in hinged suspension, at its heel in juxtaposition to the base 4 by a cord or wire 20, which extends from each side thereof and is 80 fixed at its outer end to the frame *b*. To the outer free portion of the rudder *i* at each side thereof is fixed a cord or wire 21, which extends to within reach of the aeronaut on the platform *d*, whereby the rudder *i* can be directed 85 on its hinge 20 to the right or left, as desired.

If desired, a second rudder may be likewise arranged at the forward end of the air-ship.

Within the gas-bag *a* is preferably arranged 90 an auxiliary bag *k*, composed of some light and elastic material and adapted to be inflated and expanded by air which enters the bag *k* through a tube 22, attached at one end thereto and thence coiled on the floor 4 of the gas-bag *a*, from which it passes through a gas-tight hole in the fabric to an air-pump (not shown) operated by the aeronaut or by the 95 motors *e* on the platform *d*, as found most suitable.

To the front and rear ends of the bag *k*, 100 which lies loosely on the floor 4 of the gas-bag *a*, are attached cords 23 and 24, which extend through gas-tight holes in the fabric 5 at the front and rear ends, respectively, of the gas-bag *a* to within reach of the aeronaut, 105 whereby the bag *k* when inflated by the air supplied thereto through the tube 22 to the size shown by full lines in Fig. 1 or to that indicated by the broken lines can be moved forward or rearward along the floor 4, and 110 thereby displace the gas within the bag *a* accordingly and cause it to flow toward the opposite end of the bag *a*, which rises at this end in obedience thereto. Moreover, by inflating the bag *k* with air the gas in the bag *a* presses 115 proportionately upon and maintains the tautness of the fabric 5.

What I claim as my invention, and desire to 120 secure by Letters Patent, is—

1. In an air-ship, the combination of a gas-bag having a suitable frame, and having its bottom surface flat and normally inclined upward longitudinally from its rear end, a platform dependent from the frame, a shaft located beneath the gas-bag, bearings fixed to 125 the frame for the said shaft, a propeller fixed on the shaft, an auxiliary bag located within the gas-bag and having an elastic envelop, means for admitting air to the auxiliary bag, and for moving the auxiliary bag within the 130

gas-bag from the said platform, and means for rotating the shaft, substantially as described.

2. In an air-ship, the combination of a gas-bag, a frame surrounding the gas-bag—means for securing the gas-bag to the frame, an auxiliary bag located within the gas-bag and having an elastic envelop, a cord attached to each end of the auxiliary bag and extending therefrom through a gas-tight hole in the corresponding end of the gas-bag, to the said plat-

form, and means for admitting air to the auxiliary bag, substantially as described.

In testimony whereof I have signed my name to this specification in the presence of two subscribing witnesses.

HENRY E. HONEYWELL.
